UNITED STATES PATENT OFFICE

2,598,347

FLATIRON SUPPORTING AND CLEANING DEVICE

Charles Butera, Los Angeles, Calif.

Application November 13, 1950, Serial No. 195,309

4 Claims. (Cl. 38—142)

1

This invention relates to new and useful improvements in flat iron supports and rests and the primary object of the present invention is to provide a flat iron support and cleaning device whereby a flat iron may be effectively cleaned and polished in a convenient manner.

Another important object of the present invention is to provide a flat iron supporting and cleaning device composed of two hingedly connected substantially rectangular and open frame members each having a peripheral sloping seat and a surface treating member or pad positioned in the seats and accessible through the openings in the frame members when the latter are disposed one above the other.

A further object of the present invention is to provide a flat iron supporting and cleaning device of the aforementioned character including a ribbed platform having depending lugs that will enter depressions formed in supporting legs for one of the frame members to center the platform over the frame members when the frame members are disposed one above the other.

A still further aim of the present invention is to provide a flat iron supporting cleaning and polishing device that is simple and practical in construction, strong and reliable in use, small and compact in structure, inexpensive to manufacture, and otherwise well adapted for the purposes for which the same is intended.

Other objects and advantages reside in the details of construction and operation as more fully hereinafter described and claimed, reference being had to the accompanying drawings forming part hereof, wherein like numerals refer to like parts throughout, and in which:

Figure 1 is a perspective view of the present invention, the ribbed platform removed and the frame members hinged apart and the surface treating members raised;

Figure 2 is a perspective view of the rubber platform forming part of the present invention;

Figure 3 is a top plan view of the invention showing the frame members disposed one above the other and the platform supported upon the frame members, and with part of the platform broken away; and,

Figure 4 is a longitudinal vertical section view taken substantially on the plane of section line 4—4 of Figure 3.

Referring now to the drawings in detail, wherein for the purpose of illustration, there is disclosed a preferred embodiment of the present invention, the numerals 10 and 12 represent a pair of elongated preferably rectangular frame mem-

2

bers each having a peripheral sloping seat 14 about their openings 16.

5 The frame members 10 and 12 are hinged together, as at 18, to permit the frame member 10 to be folded over the frame member 12 with the frame members in contacting relationship as shown in Figure 4 of the drawings.

One side of the frame member 12 supports a U-shaped hand grip 20 to permit convenient 10 handling of the device and a resilient clip or arm 22 is fixed to the frame member 12 within the confines of the hand grip 20 to yieldingly engage the frame member 10 and return the frame members disposed one above the other and in contacting relationship.

A substantially rectangular rigid, surface 20 cleaning and polishing member or pad 24 is hinged along one of its longitudinal edges to the hingedly connected sides of the frame members, 25 as at 26. The surface cleaning and polishing member 24 is provided with a double beveled peripheral edge 28 that is positioned in the seats 14 when the frame members 10 and 12 are disposed one above the other, and the flat surfaces of the member 24 extend through the openings 16 in the frame members to be engaged by the undersurface of a flat iron (not shown). One surface or wall 30 of the member 24 is composed of an abrasive material such as emery whereas the 30 other surface or wall 32 of the member 24 is of soft wax cloth material constituting a polishing surface. The peripheral edges of the walls 30 and 32 are joined, by any suitable means, at the apex of the beveled edge of member 24.

35 Each of the frame members 10 and 12 is provided with a plurality of supporting legs or feet 34 and the supporting legs of the frame member 10 are provided with axial depressions or recesses 36 that receive lugs 38 that depend from a ribbed or corrugated platform 40. The platform 40 is shaped to conform to the curvature of a flat iron and is centered over the frame members by the interconnecting means 34, 36, 38, when the frame members are disposed one above the other.

40 The platform 40 is provided with a pair of up-standing side flanges 42 that will tend to retain a flat iron upon the platform or more specifically the ribbed surface of the platform.

In practical use of the invention, the device 50 is assembled as shown in Figure 4 for use of the platform for supporting a flat iron. The platform is removed and the surfaces or walls 32 and 30 are selectively and sequentially rubbed by the undersurface of a flat iron to clean and 55 polish the undersurface of the flat iron.

In view of the foregoing description taken in conjunction with the accompanying drawings it is believed that a clear understanding of the device will be quite apparent to those skilled in this art. A more detailed description is accordingly deemed unnecessary.

It is to be understood, however, that even though there is herein shown and described a preferred embodiment of the invention the same is susceptible to certain changes fully comprehended by the spirit of the invention as herein described and the scope of the appended claims.

Having described the invention, what is claimed as new is:

1. A flat iron supporting and cleaning device comprising a pair of substantially rectangular frame members, means hinging said members together and permitting one of the members to be folded over the other of the said members and a rigid surface cleaning and polishing member also attached to said frame members by said hinge means, said frame members each having a peripheral seat against which said surface cleaning and polishing member is seated when the frame members are disposed one above the other, said frame members each having an opening through which said surface cleaning and polishing member is exposed when the frame members are disposed one above the other.

2. The combination of claim 1 and a clip carried by one of said frame members and engaging the other of said frame members to hold the frame members one above the other.

3. A flat iron support comprising a pair of hingedly connected frame members, supporting legs carried by and depending from the under-

5 side of each of said frame members, the legs carried by one of said frame members having recesses therein, a platform adapted to support a flat iron, and lugs on said platform received in said recesses when said one of said frame members is disposed over the other frame member with its legs projecting upwardly and located on the opposite side of the support from the legs of the said other of said frame members.

10 4. A flat iron supporting and cleaning device comprising a pair of open substantially rectangular frame members, each of said frame members including a continuous sloping seat, said seats surrounding the openings in said frame members, hinge means securing the frame members together and permitting one of the frame members to be folded over the other of said frame members, supporting legs for said frame members, and a rigid surface cleaning and polishing member having a beveled peripheral edge positioned in said seats and disposed in registry with the openings in said frame members when the frame members are disposed one above the other.
